METALLIC TUBE FURNACE

Abe J. Perle, Orange, N. J., assignor to Persiro Manufacturing Corp., Newark, N. J., a corporation of New Jersey

Application October 4, 1946, Serial No. 701,153

1 Claim. (Cl. 158—1)

1. This invention relates to water and steam heating plants, and more particularly to a combined boiler and burner unit adapted for use in homes. The invention consists of a metallic combustion tube and a flue tube extending along the length thereof, forming an annular space between the tubes, said flue tube having its receiving end abutting the periphery of a flow reverser to receive in said annular space the products of combustion from the flow reverser and guide them along the exterior of the combustion tube and over any incandescent part thereof, and a spinner disposed between the discharge end of the combustion tube and the receiving end of the flue tube to spiral the products of combustion directed by the flow reverser into the annular space between the tubes, for preventing the combustion tube from reaching a harmful high temperature.

The invention will be further described, an embodiment shown in the drawings, and the invention will be finally pointed out in the claim.

In the accompanying drawings, in which like reference characters indicate corresponding parts throughout the various views:

Figure 1 is an end elevation view of the boiler arrangement, showing the burner and air head connected thereto and the blower for supplying air to the head.

Figure 2 is a longitudinal cross-sectional view taken through the combined boiler and burner unit, showing the burner head in section, but showing in side elevation the motor and the air and fuel pumps; and

Figure 3 is an enlarged fragmentary front elevational view of the spinner, and

Figure 4 is a view taken on the line 4—4 of Figure 3 and looking in the direction of the arrows, the view illustrating the angular arrangement of the spinner blades.

Referring now to the figures, 10 represents a boiler shell or casing having an inlet 11 at its bottom and an outlet 12 at its top. The ends of the boiler casing are closed by heads 13 and 14. On the head 13 is a casting 15 adapted to receive water through an opening 16 at the bottom of the head and direct same upwardly to an opening 16' at the top of the head. This casting 14 has an opening 17 therein adapted to support a combustion tube 18. The combustion tube is formed of a "high chrome," type 446 stainless steel which is resistant to oxidation up to a temperature of 2150 degrees Fahrenheit.

The combustion tube 18 extends into the boiler and is surrounded by a circular fire tube or boiler flue 19 having its walls rigidly spaced from the combustion tube so as to form a surrounding annular chamber. This flue 19 is connected at its ends to the head members 13 and 14 and has fins 21 for projecting the heat into the water mass of the boiler 10. Above the flue or fire tube 19

are three spaced flue or fire tubes 22, each having heat projecting fins 23 on the outer periphery surface thereof.

The gases which are projected through the combustion tube 18, by means to be presently described, pass to the rear end of the boiler and are thrust against a refractory deflecting means or baffle 24. This deflecting member or baffle 24 is held on the head 14 by a casing 25 having a main chimney 26 therein. The refractory return baffle 24 is brought to a high incandescent heat so that any unburned fuel gases which may strike it are oxidized before the gases are caused to flow counter-current through the annular chamber. Between the end of the combustion tube adjacent the baffle 24 and the flue 19 there is provided a spinner 27 which imparts a tangential component to the gas flow to make up for any whirl which may have been lost by impingement on the baffle 24 and the reversal of the gas flow after leaving the end of the combustion tube 18. The spinner 27 is rigidly connected to the inside of flue 19 but sufficiently large on its inside diameter to allow the free sliding of combustion tube 18 through its center. The combustion tube 18 is thus supported at both ends but free to expand and contract as required. The spinner 27 embodies an annular collar having a plurality of spaced angularly disposed blades 27' projecting from a face thereof, the angular disposition of said blades being such as to induce rotative peripheral movements to the products of combustion flow.

The products of combustion or gases flow in a counter-current direction through the annular chamber and impart heat to the wall thereof which heat is in turn transferred by convection to the water body of the boiler. The gases are then collected in a chamber 28 within the casting 15 and are directed upwardly to the flue tubes 22, each of which contains a spirally shaped element or spinner 29, which imparts a spiral travel to the gases insuring the complete washing of the inside of the tube walls and maximum heat transfer to the boiler water. On leaving the fire tubes 22, the gases will then go to the chimney 26 for dissipation to the atmosphere.

On the structure 15 and communicating with the fire tube 18 is a combustion head 31 comprising an air inlet portion 32 and an oil inlet structure 33, supporting a spray nozzle.

A slow burning flame is started and this mass is whirled through the combustion tube, being thrown circumferentially and tangentially against the combustion tube by centrifugal force, heating this tube to a red heat. Once the combustion tube reaches this elevated temperature, it acts as a pilot to ignite any oil particles which may not have been touched off by the initial ignition of the fuel particles at the combustion

head. The red hot walls of the combustion tube also act as a converter to materially assist in the further oxidation of the carbon monoxide formed in the initial stages of the combustion and converts the monoxide to carbon dioxide. This secondary burning of carbon monoxide increases the overall efficiency of combustion by releasing more of the energy stored in the fuel. The burning gases, because of the rotary components imparted by passage through the spinner 27, are thrown centrifugally against the primary heating surface of the boiler flue 19. This insures a high rate of heat transfer through the broiler flue 19 into the water mass of the boiler. As the hot products of combustion spiral through the annular chamber between combustion tube 18 and boiler flue 19 they become cooled due to heat transfer through the boiler flue to the surrounding water. The gases thus cool the outside of the combustion tube 18 and prevent said tube from reaching an excessively high temperature at which the stainless steel might be melted or oxidized. In addition, the combustion tube 18 is cooled by the transfer of radiant heat to boiler flue 19 as previously explained, as well as by conduction through contact with the boiler head casting 15 and spinner 27 at either end. The combustion tube operates at a temperature of 1700 to 1850 degrees Fahrenheit which is high enough to catalyze the oxidation of carbon monoxide to carbon dioxide, but at the same time low enough to prevent oxidation or melting of the combustion tube 18. The fins 21 and 23 afford an extremely large surface to complete the transfer of heat from the tubes to the boiler water. The tubes are so placed that the extended heating surface sections completely cover the cross-section of the boiler. The multitude of fins provides a very large total heating surface so disposed as to "comb" the entire cross-section of the boiler and break up any steam pockets rising from the outside surfaces of either boiler flue 19 or fire tubes 22. This feature eliminates "priming" or the entrainment of water with the steam delivered from the boiler which is an evil usually inherent to the design of small or rapid steaming boilers.

Additional heating surface, as indicated at 64, is gained where the gases contact the back wall of casing 14. While detailed changes may be made in the construction of the various parts and in the arrangement of same, it shall be within the spirit and scope of the present invention as defined in the appended claim. Although the drawings shown indicate the use of oil or other liquid fuel, it is to be understood that the invention is suitable for the combustion of gaseous or liquified hydrocarbon fuels by substitution of a nozzle suitable to fuel being burned.

The invention provides a boiler burner unit which will have a high chrome stainless steel combustion tube so designed and arranged as to give the following advantages. First, the design of the combustion tube and its placement in the boiler in conjunction with the special fuel and air handling parts in the combustion head, allows the complete and efficient combustion of the fuel in a fraction of the furnace volume heretofore found impossible in commercial practice for domestic heating plants. Secondly, the design and placement of the combustion tube is such that the tube very rapidly reaches an operating temperature in the incandescent range and is held at this temperature by a counter-current flow of cooling gases around its periphery. Be-

cause this combustion tube is in close proximity to a water backed heating surface it is able to effect a transfer of its radiant heat to the cooler surface. Since the rate of radiant heat transfer varies directly as the fourth power of the absolute temperature, it can readily be seen that if a slight increase in operating temperature above the normal should be encountered in the metal surface of the combustion tube, the immediate increase of radiant heat transfer to the surrounding furnace flue would cool the combustion tube back to the normal again. This self-regulatory feature of the design makes possible the use of a thin wall metallic combustion tube instead of present day heavy fragile refractories.

This invention provides a boiler-burner unit which is so designed as to employ a minimum of refractory material. The entire combustion tube and refractory may be factory assembled as integral parts of a "packaged" unit. This eliminates installation work by the consumer of refractories and assures a better as well as a more economical job.

The invention provides a boiler-burner unit which will operate at a high "positive overfire pressure," i. e. above atmospheric. This assures more rapid and complete combustion of the fuel. The boiler is so designed that despite the "positive overfire pressure" none of the products of combustion may escape from the boiler from any opening other than the chimney during the operation of the boiler.

The invention provides a boiler-burner unit which is made of welded steel plate, all heat transfer surfaces being of stainless steel to prevent corrosion which would gradually decrease the rate of heat transfer. The assembly includes a boiler flue to separate the heating flame from the water and which is adapted to contain a central combustion tube through which the flames are projected onto a deflecting means of high temperature retaining molded refractory material. The deflecting means serves to reverse the flow of the burning gases and products of combustion, and, due to the refractory nature of the material, it reaches an incandescent condition. Any carbon monoxide, as yet unburned, upon becoming intimately contacted with the incandescent surface is immediately converted to carbon dioxide. The heated products of combustion are then caused to flow counter-current through an annular chamber surrounding the combustion tube and thence upwardly and through a plurality of spaced flue tubes arranged above the annular chamber and extending horizontally through the boiler shell, the flow of the products of combustion being in reverse direction to that of the annular chamber flow. The products of combustion upon egress from the flue tubes are discharged through a chimney provided in the boiler shell.

The burner is the subject matter of a copending divisional application filed on March 28, 1947, under Serial Number 737,862 and no claim to the burner is made herein.

I wish it to be understood that I do not desire to be limited to the exact details of construction shown and described, for obvious modifications will occur to a person skilled in the art.

I claim:

In a metallic tube furnace, the combination with a metallic cylindrical combustion tube of stainless steel of high chrome type 446, adapted to temperatures of 2150° F., having one end to receive burning fuel and air, and having its

other end open to discharge the products resulting from the combustion thereof, a flow reverser of refractory material spaced from the discharge end of the combustion tube, and in the path of the discharging products of combustion, to reverse the flow of said products, a metallic cylindrical flue tube concentrically spaced from the exterior of the combustion tube and extending along the length thereof, forming an annular space between the tubes, and having its receiving end abutting the periphery of the flow reverser to receive in said annular space the products of combustion from the flow reverser and guide them along the exterior of the combustion tube and over any incandescent part thereof, of a spinner disposed between the discharge end of the combustion tube and the receiving end of the flue tube to spiral the products of combustion directed by the flow reverser into the annular space between the tubes, for preventing the combustion tube from reaching a harmful high temperature.
